UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,560, dated March 3, 1891.

Application filed February 6, 1891. Serial No. 380,519. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing forming part thereof.

10 In the drawing is shown a side elevation of a cane or umbrella handle illustrating my new design.

The shank A is formed with a swelling portion of highly-ornamented work G. It is bounded on the bottom by an annular band F, ornamented to a slight extent, and on the top with a smooth annular band E. Extending upwardly from the band E is a loop B, the

base of which is formed with a series of grooves or ribs D. The narrow end of the 20 loop B extends downward and is united with the part D near the annular band E and is finished with a scroll ornamentation C.

The handle may be made of any suitable material. 25

Having now described my new design, what I claim as new, and desire to secure by Letters Patent, is—

The design for cane or umbrella handles, substantially as herein described and shown. 30

In testimony of which invention I have hereunto set my hand.

HENRY O. SCHMIDT.
